UNITED STATES PATENT OFFICE.

MARSHMAN W. HAZEN, OF NEW YORK, N. Y., ASSIGNOR TO STANDARD TYPEWRITER COMPANY, A CORPORATION OF NEW YORK.

CARRIAGE FOR TYPE-WRITING MACHINES.

1,092,837.

Specification of Letters Patent.

Patented Apr. 14, 1914.

Original application filed June 23, 1908, Serial No. 439,967. Divided and this application filed June 30, 1909. Serial No. 505,248.

To all whom it may concern:

Be it known that I, MARSHMAN W. HAZEN, a citizen of the United States, and a resident of New York, county and State of New York, have invented certain new and useful Improvements in Carriages for Type-Writing Machines, of which the following is a full, clear, and exact description.

This invention relates more particularly to line-lock mechanism for typewriting machines, and is a division of my pending application Serial No. 439,967, filed June 23, 1908.

The primary object of the invention is to provide simple and efficient means whereby the carriage may be positively locked at the end of a line and then permitted to have a further movement in case it is desired to add one or more letters or characters to finish a word at the end of the line, and then again automatically lock the carriage against further movement.

A further object of the invention is to provide simple and efficient means having a part held to the carriage and movable therewith, and another part not movable with the carriage in its letter spacing movement and which is adapted to be engaged by the first-mentioned part to stop or limit the action of the keys and thus lock the carriage against movement at the end of a line.

With these and other objects in view, the invention will be hereinafter more particularly described with reference to the accompanying drawings, which form a part of this specification, and will then be pointed out in the claims at the end of the description.

In the drawings, Figure 1 is a longitudinal section of one form of machine embodying the invention. Fig. 2 is a rear elevation of the machine. Fig. 3 is an inverted plan view of the carriage removed from the machine, showing one form of line-lock together with a part of the escapement mechanism. Fig. 4 is an enlarged vertical section through a part of the carriage, showing a part of the escapement mechanism; and Fig. 5 is a fragmentary view, showing a different form of means for locking the carriage at the end of a line.

The frame 10 may be of any suitable construction and may be provided with a plu-

rality of bars 11 to which are pivotally held the key-levers 12, and these key-levers 12 are normally forced in one direction by the springs 13 and at their inner ends are connected by links 14 to the type-bars 15. These type-bars 15 are pivoted at 16 to a bracket 17, and have their type-heads 18 adapted to engage the work passing about the platen 19, which latter is suitably supported on the carriage 20.

As an escapement mechanism and means for operating the same the carriage 20 is provided with a rack-bar 21 under the same, and this rack-bar has the usual ratchet-shaped teeth in which are adapted to move the escapement pawls or dogs 22 and 23, Figs. 1 and 4, one of which, as 22, is fixed and the other, as 23, is movable, and both dogs are adapted to permit the carriage to move the distance of a single tooth as usual when said dogs are moved laterally transversely of the rack-bar. The dogs 22 and 23 are carried by an arm 24 which is pivoted at 25 to the carriage bed 26 and has its opposite end, as 27, guided in a slot 28 of a bracket 29 so as to permit the dogs to be moved laterally of said rack-bar allowing the carriage to escape one tooth at a time and causing the dogs to be swung in an arc of a circle across the face of the rack in the same plane as the rack instead of in a direct line thus making the dogs engage the rack teeth at one point instead of along the entire surface thereby materially reducing the wear and friction thereof. A spring as 30 is arranged on the carriage bed, Fig. 4, and has one end passing through the fixed dog 22 and is so arranged that it will only force the dog and the arm in one direction, and secured to the arm 24 is a stop 31 which is adapted to engage a projecting part 32 of the movable dog 23, in order to limit its movement, the said dog being normally held against movement in one direction by the spring 33, and in the opposite direction by a spring 34, though instead of the two springs a single spring may be employed if desired.

The escapement may be operated no matter what position the carriage is in. This is secured by arranging a movable bar 35 of the escapement-operating frame transversely of the machine. A collar or projecting part 36 located on the bar 35 is

adapted to engage the head 27 of the arm 24 so as to move the escapement pawls against the action of the spring 30. The bar 35 is held in the upper end of the levers or arms 37 of the escapement frame and said arms are pivoted on opposite sides of the machine to a transversely-extending rod or bar 38, each of said levers or arms 37 being provided with a vertical slot 39 at the upper end thereof. A bell-crank or angular lever 40 is pivoted at 41 to a part of the machine frame on each side thereof, and has one end, as by a screw 42, guided in the slot 39 of the lever or arm 37 and its other end connected by a link or rod 43 to a universal bar 44. This universal bar 44 extends transversely of the machine over each key lever so that as each key is depressed it will raise the bar 44 and move the bell-crank levers 40 on their pivots 41, and by means of the shoulder screws 42 in the slots 39 of the levers 37 will throw the escapement-moving bar 35 outward and thereby move the escapement arm 24 carrying the pawls against the tension of the spring 30. The parts thus far described may be of any desired construction.

It is desirable to lock the carriage at the end of a line, and it is also desirable to permit the carriage to have a maximum throw to add one or two letters to any of the lines in case the word is not finished properly. This may be effected in various ways. As shown, Figs. 2 and 3, the arm 45 to which the flexible connection 46 from the escapement drum 47 is attached, and which rings the bell, has a dog or locking device 48 pivotally held thereto and normally pressed inward by a spring 49. This device extends outward on opposite sides of its pivoting point, Figs. 3 and 6, one part, as at 50, to serve as a handle and the other part, as 51, being provided with a substantially U-shaped slot 52. A rod or device 53, Fig. 3, is rotatably held in the brackets 54 secured to the carriage bed and under the same, and said rod has one end 55 bent to lie normally in a horizontal plane, and its other end 56 bent or made to extend at right angles thereto so as to project above the carriage bed on the outer surface thereof, as shown in Fig. 2. The rod may also be bent or formed with a part 57 to position the ends 55 and 56, the latter end being adapted to be engaged by the detent or device 48 carried by the arm 45 and movable with the carriage, while the end 55, when the rod is engaged by the device 48, is forced downward on the outer side of the bar 35 so as to prevent the same from being moved by the keys, thus preventing the escapement being operated and locking the carriage. If the device 48 is released by the handle end 50, the carriage may still be moved a certain number of spaces until the rod is again engaged

by the shoulder 58 of said device, the distance the carriage is permitted to move being determined by the length of the slot or opening in the device or the distance between the two abutments. The rod or element 53 is normally held in one position by a spring 59, and its end 56 is first engaged by the end of the device 48, and when the latter is released, as can be done very readily, the said end 56 will enter the slot in the device 78 until the shoulder or abutment 58 engages the same, and depresses it when the carriage will be positively locked. By this means additional letters may be printed at the end of a line to complete a word if desired and the carriage again automatically stopped.

Fig. 5 shows how the end of the device 48, instead of striking the end 56 of the rod 53 is made to engage one end of a pivoted arm or lever 60. This arm or lever is pivoted under the carriage bed, and is forced in one direction by a spring 61. This lever has one end adapted to be engaged by the device 48, and has its inner end adapted to be forced in the path of movement of the arm 24 carrying the escapement pawls 22 and 23, and thereby prevent movement thereof through the bar 35 and mechanism hereinbefore described.

While I show and describe features other than those relating to the line-lock mechanism, such features are not claimed herein as they form subject matter of separate co-pending applications among which are feed mechanism, Sr. No. 499,893, filed June 3, 1909; line-spacing mechanism, Sr. No. 499,874, filed June 3, 1909; and carriages, Sr. No. 439,967, filed June 23, 1908.

Having thus described my invention, I claim as new and desire to secure by Letters Patent:—

1. In a typewriting machine, the combination with a support, of a carriage adapted to move along said support, a pivotally held device having a substantially U-shaped slot and movable with the carriage, escapement mechanism, a rod rotatably held under the carriage and having one end adapted to be engaged by the device and the other end adapted to be moved in the path of a part of the escapement mechanism to stop the action thereof and thereby prevent further movement of the carriage and when said device is released permits a further movement of the carriage determined by the length of the slot.

2. In a typewriting machine, the combination with a support, of a carriage adapted to move along said support, escapement mechanism, means for operating said escapement mechanism, a rod rotatably held under said support and having a projecting end adapted to be moved in the path of a part of the escapement mechanism to stop

- the action of the same, a spring normally forcing the rod in one direction, said rod having an end projecting upwardly, and a device having an open portion and pivotally held to the carriage, and adapted to engage the end of said rod to rotate the same and stop the escapement and when released to permit a further movement of the carriage and then again engage the rod and stop the carriage.
3. In a typewriting machine, the combination with a support, of a carriage adapted to move along said support, escapement mechanism, means for operating said escapement mechanism, a rod rotatably held under said support and having a projecting end adapted to be moved in the path of a part of the escapement mechanism to stop the action of the same, a spring normally forcing the rod in one direction, said rod having an end projecting upwardly and means for limiting the rotary movement of said rod and a device pivotally held to the carriage adapted to engage the end of said rod to rotate the same and stop the escapement and when released to permit a further movement of the carriage and then again engage the rod to stop the carriage.
4. In a typewriting machine, the combination with a support, of a carriage adapted to move along said support, escapement mechanism, means for operating said escapement mechanism, a rod rotatably held under said support and having a projecting end adapted to be moved in the path of movement of the escapement mechanism to stop the action of the same, a spring normally forcing the rod in one direction, said rod having an end projecting upwardly, a device having a slot therein and pivotally held to the carriage adapted to engage the end of said rod to rotate the same and stop the escapement and when released to permit a further movement of the carriage and then again engage the rod, and a spring normally forcing said device in one direction.
5. In a typewriting machine, the combination with a support, of a carriage adapted to move along said support, means for moving the carriage for letter spacing, means mounted upon the support adapted to engage a part of the carriage letter spacing means to lock the carriage against movement at the end of the line, and a device having a substantially U-shaped slot pivotally mounted to move with the carriage and having a part thereof adapted to engage the carriage locking means and when released to permit a further movement of the carriage and then again automatically lock the same.
6. In a typewriting machine, the combination with a support, of a carriage adapted to move along said support, means for moving the carriage for letter spacing, means mounted upon the support adapted to engage a part of the carriage letter spacing means to lock the carriage against movement at the end of the line, and a pivotally held device mounted on the carriage and having a slot and two abutments pivotally mounted to move with the carriage and having one abutment adapted to engage the carriage locking means and when released to permit a further movement of the carriage and then again automatically lock the same by engagement with the other abutment.
7. In a typewriting machine, the combination with a support, of a carriage adapted to move along said support, means for moving the carriage for letter spacing, means mounted upon the support adapted to engage a part of the carriage letter spacing means to lock the carriage against movement at the end of the line, and an adjustable device mounted on the carriage and having two abutments one of which is adapted to engage the carriage locking means to lock the carriage against movement and when released to permit a further movement of the carriage and then again automatically lock the same by engagement with the other abutment.
8. In a typewriting machine, the combination of a support, a carriage adapted to move along said support, means for moving the carriage for letter spacing, means mounted upon the support adapted to engage a part of the carriage letter spacing means to lock the carriage against movement at the end of the line, an adjustable pivoted device having a slot and two abutments mounted to move with the carriage and having one abutment adapted to engage the carriage locking means and when released to permit a further movement of the carriage and then again automatically lock the same by engagement with the other abutment and a spring tending normally to hold the device in an engaging position.
- This specification signed and witnessed this 28th day of June A. D. 1909.
